(57) CLAIM

The ornamental design for a swimming cap as shown and described.

DESCRIPTION

FIG. 1 is a front elevational view of a swimming cap showing us new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a sectional view along 9-9 as indicated in FIG. 1; and,

FIG. 10 is a sectional view along 10-10 as indicated in FIG. 1.

The broken lines shown illustrate portions of the swimming cap that form no part of the claimed design.
